TOILET TRAINING CHAIR

Norman E. Roe, Sierra Madre, Calif., assignor to Majestic
Seat Company, Inc., Newnan, Ga., a corporation of Georgia

Filed Mar. 19, 1963, Ser. No. 74,079

Term of patent 14 years

(Cl. D4—5)

FIG. 1

FIG. 2

Des. 201,427

PAGE 2

FIG. 5

FIG. 4

FIG. 5

FIG. 1 is a perspective view of a toilet training chair showing my new design.

FIG. 2 is a side elevation view.

FIG. 3 is a top plan view.

FIG. 4 is a front elevation view.

FIG. 5 is a rear elevation thereof.

The dominant features of my design reside in the portions shown in full lines.

I claim:

The ornamental design for a toilet training chair, as shown and described.
